J. METTLER

PREPAYMENT METER FOR GAS, WATER, ELECTRICITY, OR SIMILAR SUPPLY

Filed April 6, 1922

Inventor,
Josef Mettler,
By B. Singer, Atty.

UNITED STATES PATENT OFFICE.

JOSEF METTLER, OF ZUG, SWITZERLAND, ASSIGNOR TO THE FIRM LANDIS & GYR LTD., OF ZUG, SWITZERLAND.

PREPAYMENT METER FOR GAS, WATER, ELECTRICITY, OR SIMILAR SUPPLY.

Application filed April 6, 1922, Serial No. 550,141, and in Switzerland April 12, 1922.

The invention relates to a prepayment meter of the type in which a spring is put into tension by actuating the prepayment mechanism after the insertion of a coin, this spring controlling the supply. This invention has, however, several advantages in comparison with already known constructions of prepayment meters. First there is no need to provide a coin locking device, i. e. a device preventing the consumer from inserting, at one operation a higher number of coins than is required. Furthermore the design is very simple as there is a spiral spring which, together with a rotating switch built up as a solid unit, produces a crank motion; and only one stop is required for this switch.

In the accompanying drawings Figure 1 is a plan, partly in section, of a prepayment meter constructed and arranged in accordance with this invention.

Figure 2 is a vertical transverse sectional view of the same taken on the plane indicated by line II-II of Figure 1.

25 Figure 3 is a detail plan partly in section of the lever 28 and associated elements.

Figure 4 is a detail plan of the spindle and associated elements.

30 Figure 5 is a detail transverse sectional view of the same on a plane intersecting the slot 9.

In the preferred form shown by the drawings, 1 is a base plate and 2 the cover of the case of a prepayment meter for electricity. 3 is a Ferraris disc and 4 the counting train of the meter mounted in the same case as the prepayment mechanism.

A frame 6 is fixed to the base plate 1 by means of the support 5, in which is journaled a spindle 7. This spindle 7 carries a toothed wheel 8 which is free to turn through a certain angle on the same, and for this purpose a slot 9 is cut in the hub of the toothed wheel 8 (Figs. 4 and 5). In 40 this slot slides the head of a screw 10, screwed into the spindle 7. The torsion spring 11, which is fastened at one end to the toothed wheel 8, and at the other to the spindle 7, tends to turn the toothed wheel 8, so that one end of the slot 9 presses against the screw 10.

The spindle 7 is coupled with a coin receiving device 12, mounted on the cover 2. The toothed wheel 8 is in mesh with the

toothed wheel 13 which, in turn, is coupled by a flexible spindle 14 to one of the figure wheels 15 of the counting train 4. The circular rotating piece 16 is provided with a toothed segment 17, and is rigidly attached to the spindle 18, this spindle carrying a wing shaped switch 19 and having a transverse contact piece 20. 21 are contacts mounted on the flat spring 22 which, in turn, are rigidly fixed. The circular rotating piece 16 is provided with a projecting piece 23, and a crank pin 24 on which the coil spring 25 acts.

The projecting piece 23 acts together with the stop face 26 of a spindle 27, which face can be clearly seen in Fig. 2. The spindle 27 carries a lever 28, the end of which is bent downwards to form a lug 28'. With this bent end the lever 28 presses against a horizontal spindle 29. The spindle 29 is carried by the bracket 30 which is attached to the frame 6. The end 31 of the spindle 29 is threaded and works in the threaded sleeve 33, which may be fixed in position by means of the lock-nut 32. The spindle 29 has a sloping face 34, the sides of which are inclined to the longitudinal axis of the spindle 29, and this spindle 29 is driven by a spindle 35 of the counting train 4 which spindle 35 in turn is in conjunction with several spindles of the counting train 4, by means of a combination of gears comprising a differential gear. The spindles 29 and 35 are coupled by means of a driver pin 36 of insulating materials, whereby this pin 36, fixed to the spindle 35, projects through a slot in a cross piece 37 which, in turn, is rigidly attached to the spindle 31. A torsion spring 38 wound round the spindle 27 tends to turn the spindle 27 with the lever 28, so that the lug 28' of the latter moves away from the spindle 29 and presses against a stop 39.

In the drawings switch mechanism is shown in its "on" position, i. e. after the insertion of coins the spindle 7 has been turned in the direction of the arrow (Fig. 2) whereby the spring 25 has been turned, thus bringing the contact piece 20 of the switch 19 into contact with the fixed contacts 21. The lever 28 and its spindle 27 are locked by the spindle 29, and therefore the stop 23 is held in contact with the stop face 26.

When the amount of electricity, corre-

spending to the total value of the coins inserted has been consumed, the spindle 29 is turned in the direction of the arrow 40. As a result the spindle 29 is displaced in the direction of the arrow 41, due to its working in the threaded sleeve 33. When the spindle 29 is displaced, its sloping face 34 comes into the reach of the lug 28' and this lug is immediately released when the longitudinal edge of the slope 34 slips under the edge of the lug 28'. The spindle 27 is now free to turn under the tension of the spring 25, the stopping face 26 thus releasing the stop cam 23, while the spindle 18 with the switch 19, is turned so that the contacts are opened and the supply of electricity cut off.

The spring 38 which is weaker than the spring 25 immediately returns the spindle 27, so that the lug 28' comes into contact with the stop 29. By the turning of the spindle 18 the toothed segment 17 comes into mesh with the toothed wheel 8. Owing to the somewhat elastic mounting of the toothed wheel 8 on the spindle 7, the former can be slightly moved on the latter by the action of the torsion spring 11 and in the moment when the teeth come into mesh, thus considerably reducing the action of the shock.

Should now, after insertion of a coin the spindle 7 be once more turned in the direction of the arrow, the spindle 18 carrying the circular rotating piece 16 and the switch 19 will be turned, through the wheel gear 8 and 17, until the crank pin 24 has passed its dead centre, and in this moment the geared segment 17 will disengage from the toothed wheel 8. The tension spring 25 now accelerates the turning of the spindle until the stop cam 23 comes into contact with the stop face 26, whereby also the electric circuit is closed. When turning the spindle 7, also the spindle 29 is turned in the opposite direction to the arrow 40 by means of the flexible coupling 14 and the different gears connecting the spindle 35 with the various spindles of the counting train, so that the edge of the slope 34 supports again the lug 28 and holds the spindle 27 in the position arresting the stop cam 23. It is now possible to insert further coins and by so doing the spindle 29 is axially displaced in the opposite direction to the arrow 41. The number of coins which may be inserted at one operation is greater than the consumer would be likely to insert at once (up to 100 pieces, for instance). Owing to the fact that the side walls of the sloping face 34 are inclined with regard to the longitudinal axis of the spindle 29, the lug 28' can slide surely on the circumference of the spindle 29 from the beginning of its being arrested. By displacing the threaded sleeve 33, the moment of releasing, i. e. the moment

when the prepayment meter is switched off, can be regulated exactly according to the quantity of energy consumed.

The driving pins 36 are adjusted on the shaft 35 when the counting mechanism stands on "0" for the coins still to be consumed in such manner that the flat part 34 is in the required position to cause it to release the tongue 28'. The series of numeral discs 15 represent, so to speak, exactly two numbering mechanisms, and this arrangement is not described more in detail in the specification, partly because these counting mechanisms do not form part of the present invention and partly because this arrangement is the subject matter of my copending United States application Serial No. 551,398. From this last named application it is quite evident that the two right hand series of discs which are designated at 15, form one counting mechanism, namely that counting mechanism which indicates the number of coins still to be used. The three left hand series of counting discs represent a second counting mechanism which indicates the total number of coins inserted. That counting mechanism which is of importance here and which indicates the number of the coins still to be used is driven by a differential mechanism, as described in the specification,

this differential mechanism being actuated under the influence of the driving disc of the counter and also under the influence of the coin inserting mechanism. If coins are injected then by means of the flexible shaft 14 and the differential mechanism, the counting mechanism is moved ahead, whereupon in said counting mechanism registration of the coins is effected. If, however, the value of a coin is consumed then the driving disc of the counter effects, by means of the differential, a rearward movement of the counting mechanism to an extent corresponding to the value of those coins which is still to be consumed or, in other words, the value of the prepaid coins is decreased in accordance with the consumption of current and this decrease takes place in this counting mechanism until this counting mechanism, upon consumption of current equal to the value of all of the coins, arrives at zero, and whereupon the displacement of the shaft 29, effected simultaneously with the return movement of the counting mechanism, releases the device and interrupts the circuit in which the automatic vending machine is placed.

Having now particularly described and ascertained the nature of my said invention and the manner in which the same is to be performed, what I claim is:

1. A device on prepayment meters for gas, water, electricity, or similar supply, having an axially moving spindle, provided with a sloping face, a tripping mechanism con-

- trolling the supply, this spindle having a sloping face which latter, when the spindle is displaced, releases part of the tripping mechanism and thereby causes the whole 5 tripping mechanism to be released.
2. A device on prepayment meters for gas, water, electricity, or similar supply, having an axially moving spindle with a sloping face, a tripping mechanism controlling the supply, and a lever having a lug which presses against the spindle and is released by the sloping face as the spindle is axially displaced, thus causing the tripping mechanism to be released.
- 10 3. A device on prepayment meters for gas, water, electricity, or similar supply, having a spindle provided with a sloping face, a sleeve in which said spindle is threaded, a tripping mechanism for controlling the supply and provided with a lever, the free 15 end of which is provided with a lug, which presses against the spindle and is released
- by the sloping face as the spindle moves axially forward, said tripping mechanism being provided with a spring and the lever 20 with a stop, said spring returning the tripping mechanism to its locking position when released, the said lever pressing against the stop.
4. A device on prepayment meters for electricity having a cut-out switch and a spindle on which the same is mounted, a rotating piece having a stop, a tension spring active on said piece to form a crank motion, a locking device having a controlling axially moving spindle provided with a sloping face, a tripping mechanism having a lever arranged to coact with said axially movable spindle, and also including a 25 spindle arranged to coact with the stop of the rotating piece to lock or release the latter.
